UNITED STATES PATENT OFFICE.

JEFFREY N. COLLINS, OF JACKSON, MICHIGAN.

SIDE CURTAIN FOR VEHICLES.

1,202,364.

Specification of Letters Patent. Patented Oct. 24, 1916.

Application filed July 8, 1915. Serial No. 32,668.

To all whom it may concern:

Be it known that I, JEFFREY N. COLLINS, a citizen of the United States, residing at Jackson, county of Jackson, State of Michigan, have invented a certain new and useful Improvement in Side Curtains for Vehicles, and declare the following to be a full, clear, and exact description of the same, such as will enable others skilled in the art to which it pertains to make and use the same, reference being had to the accompanying drawings, which form a part of this specification.

This invention relates to side curtains for vehicle tops and has for its object a vehicle top equipped to carry the ordinary side curtains that are now used on automobiles and at the same time afford convenient means by which the curtains can be stowed away in such a manner that the head clearance of the top is not materially affected. In fact the curtains in this new arrangement when stowed away do not hang down materially below the cross bar portions of the bows themselves.

In the side curtain arrangement heretofore used on tops for stowing away the curtains when not in use, either a folded curtain gathered together along accordion plaits has been used or a rolled curtain. Both of these arrangements make a package which is somewhat thick and bulky, especially for the reason that there are two curtains folded or rolled together in each package. It is to obviate this thick package and to thereby increase the head clearance of the vehicle top when the curtains are stowed away that the present invention is directed.

Still another feature of this invention is that the celluloid lights are not rolled but are allowed to lie out flat against the top. This prolongs their life. With the roll curtains heretofore used the lights became permanently curled by reason of resting so long in the rolled position. Of course, this difficulty was not inherent in the accordion plaited curtain but that curtain has always been found objectionable for the reason that only very small vertical lights can be employed interfering with the vision and requiring an enormous amount of extra stitching.

In the drawings: Figure 1 is a perspective of the inside of a vehicle top, one side having been cut away to get this perspective. The curtains are shown in draped position after they have been swung around crosswise of

the top preparatory to folding them and stowing them away. Fig. 2 is a similar view showing the curtains stowed away.

The vehicle top is designated *a*, the bows *b*, the deck *c*. The strainers are lettered *d* and extend from the rear bow to the front bow. The bracket irons *e* are used to slide the curtains upwardly and inwardly upon the bows. These are already old in the art. On the next to the forward bow it is advisable to also use a strap in connection with the bracket iron. However, I do not wish it understood that I limit myself to the use of a bracket iron for carrying the curtains upwardly and inwardly on the bows when transferred from a position of service to a position of storage. Other means can be used to accomplish this purpose without departing from the principle of my invention.

One of the points of novelty of the present invention resides in the employment of fastening devices *f* on the under side of the deck or strainers. These fastening devices are preferably turn buttons. They are used to hold up the free end of an envelop *g*. The permanently fastened end of this envelop is attached to one face of the cross bar portion of the bow. When the side curtain is swung around from the position of service to a position transverse of the top the free upper corner is fastened to the top or bow by a fastener *h* (preferably a turn button); this allows the curtain to drape down, as shown in Fig. 1. It may then be folded once on a horizontal line just below the celluloid light, the free end of the envelop may then be grasped and buttoned to the turn buttons *f*. In this position the curtain is laid practically flat, the celluloid lights are neither doubled nor curled while the whole package does not hang down substantially below the cross bar portions themselves. When the bows are doubled up the packages are narrow so that they are not folded in the doubling process.

For the purpose of clear illustration I have omitted a showing of the curtains on the other side of the top, but it will be understood that the curtains on the side of the top which has been cut away are stowed away in precisely the same way, the curtains being turned around the same as those shown in the drawings, and brought into coincidence with the curtains shown. These two curtains of each pair then hang together and are folded and stowed away together.

What I claim is:

1. The combination of a vehicle top provided with bows and a deck, a side curtain universally attached to the quarter of the top so as to be capable of being swung from a position of service to a position transverse of the vehicle, said curtain then being foldable along a horizontal and substantially median line, a retaining member on one edge 10 permanently attached to the top transversely thereof, and fasteners carried on the under side of the top at points spaced from the line of attachment of the envelop a distance substantially equal to one-half the 15 height of the side curtain, whereby the curtain can be folded along its horizontal median zone and the free edge of the envelop detachably engaged with the said fastener to hold the curtain in a flat single-fold position 20 against the top.

2. The combination with a vehicle top provided with bows and a deck, of a side curtain, means on the quarter of the top upon which the curtain may be swung and 25 carried to a higher and further inward position of the top transversely thereof, a fastening device carried on the under side of the top for holding the upper free corner of the curtain so as to temporarily drape 30 the curtain transversely of the vehicle, further fastening devices spaced from the line of said hanging of the curtain a distance substantially equal to half the height of the said curtain, a retaining member fastened 35 at one edge permanently to the top and detachably engageable with the second mentioned fastening members for holding the curtain flatly to the top when the same has been doubled once along a horizontal and 40 substantially median line.

3. The combination with a vehicle top provided with a deck, bows and strainers, of a side curtain, means for universally mounting one corner of the side curtain at 45 the quarter of the top, a fastening device carried on the under side of the top for engaging the free upper corner of the curtain to allow it to temporarily drape transversely of the vehicle, fastening devices carried on 50 the strainers at points spaced from the hanging line of the curtain substantially a distance equal to one-half the height of the curtain, a flexible retaining member fastened permanently at one side and detachably engageable at its free edge with the said 55 fastening devices carried by the strainers for the purpose of holding the curtain flatly to the deck when the curtain has been doubled once along a horizontal and substantially median line.

4. The combination with a vehicle top provided with bows and a deck, of a side curtain, means on the deck for supporting one corner of the curtain so that it can be 60 swung around when desired, an envelop fas-

tened at one edge to a bow, and fastening devices carried on the underside of the deck at points spaced from the bow at a distance sufficient to hold the curtain in flat condition against the deck when the same has 70 been folded together and inserted in the envelop.

5. The combination with a vehicle top provided with bows and a deck, of a side curtain, means on the under side of the deck 75 for suspending the curtain at one corner, an envelop comprising a flat web fastened to the under side of the top transversely thereof along one of its sides and free on the other three sides, and fastening devices on 80 the underside of the top in a transverse line at points somewhat spaced from the line of permanent fastening of the said web, the said fastening devices being arranged to detachably engage with the side of the web 85 opposite the side permanently fastened to the top, whereby the curtain may be gathered into said web and the web fastened to the top to hold the curtain in flat condition 90 against the top.

6. The combination with a vehicle top provided with bows and a deck, of a side curtain, means on the under side of the deck for suspending the curtain at one corner, an 95 envelop comprising a flat web fastened permanently on one side in a transverse line to the under side of the top, the other three sides of the web being free, a fastener on the under side of the top for holding the curtain temporarily draped and its upper 100 edge nearly coinciding with the permanently fastened edge of the said web which may be draped from its permanent fastening, and fastening devices in a transverse line somewhat spaced from the line of permanent fastening of the web, said fastening devices capable of engaging with the web to hold the web to the top and the curtain flat 105 against the top when the curtain has been gathered together in the web as the two 110 drapes together before the web is secured to the top by the said fastener.

7. The combination with a vehicle top provided with bows and a deck, of a side 115 curtain, means on the under side of the deck for suspending the curtain at one corner, and a flexible member fastened at one side to the under side of the top, and fastening devices on the under side of the top transversely thereof for engaging the free end of the flexible member, said fastening devices being spaced from the attached side of the flexible member a sufficient distance to allow the flexible member when held up in 120 position by the fastening devices to hold the side curtain in flat folded condition 125 against the under side of the top.

8. The combination with a vehicle top provided with bows and a deck, of a side 130 curtain, means on the under side of the

deck for suspending the curtain at one corner, and an envelop comprising a flat web fastened along one of the bows and free on the other three sides, and fastening devices 5 spaced from such bow a sufficient distance to hold the curtain in a flat thin package against the top of the vehicle when the curtain is folded into the web and the free edge of the web is attached to the said fastening devices.

9. The combination with a vehicle top provided with bows and a deck, of a side curtain, means on the under side of the deck for suspending the curtain at one corner but capable of allowing it to be carried inwardly and upwardly over the quarter, 15 an envelop comprising a flat web fastened to one of the bows, and fastening devices on a transverse line on the under side of 20 the top and spaced a sufficient distance from the said bow to allow the gathering of the curtain into a flat and thin package within the web when the said free end of the web is attached to the fastening devices.

10. The combination with a vehicle top provided with bows and a deck, of a side curtain, means at the under side of the deck for suspending the curtain at one corner but allowing it to be lifted upwardly and inwardly 25 over the quarter, an envelop comprising a

flat web fastened to the under side of the top transversely thereof and at one of its sides, and free at the other of its sides, fastening devices in a transverse line on the under side of the top and spaced a sufficient distance from the line of fastening of the said web so as to allow the curtain to be gathered within the web in a flat thin package when the web has been attached at its free edge to the said fastening devices. 35

11. The combination with a vehicle top provided with bows and a deck, of a side curtain, means on the under side of the deck for suspending the curtain at one corner, the said curtain when being turned transversely of the vehicle being carried in over the quarter, a transversely disposed web secured at one edge to the under side of the top and securable at the opposite edge in a detachable connection with the under 40 side of the top at points spaced a considerable distance from the first-mentioned attaching points of the said web so that the curtain may be gathered into a flat thin package and held close to the under side of 45 the top so as to interfere as little as possible with the head clearance in the vehicle.

In testimony whereof, I sign this specification.

JEFFREY N. COLLINS.
